UNITED STATES PATENT OFFICE.

RICHARD HAYES, OF SALT LAKE CITY, UTAH.

POUNDER-WASHER.

No. 857,567.

Specification of Letters Patent.

Patented June 18, 1907.

Application filed June 19, 1906. Serial No. 322,493.

To all whom it may concern:

Be it known that I, RICHARD HAYES, a resident of Salt Lake City, Salt Lake county, State of Utah, have invented a new and useful Improvement in Air-Pressure Washing-Machines, called a "pounder-washer," used for washing clothes, of which the following is a specification.

My invention relates to the improvement in washing machines that are used for washing clothing, or other articles, using water and air pressure, and the object of this invention, is to provide a machine, that can be operated by hand, or other motive power, and not require the constant attention of the operator. I attain these objects by the improvements shown in the accompanying drawings in which similar letters of reference indicate like parts throughout the several figures.

Figure 1. Is the side elevation. Fig. 2. Is a plan view of the washer. Fig. 3. Is a vertical section on line z, of Fig. 2. Fig. 4. Is a top view of the washer below line z, x, of Fig. 1. Fig. 5. Is an enlarged detail vertical section of the actuating bar and its attachments. Fig. 6. Is an enlarged detail vertical section of the lower part of the vertical bar, hub and cap-nut. Fig. 7. Is an enlarged detail view of the guide-ring, plate and lug.

The tub A, made of suitable material, is provided with legs l, l, etc. with rollers r, r, etc., and fitted with a tight closing top B. The top B has well secured thereon the working mechanism of the washer, that consists of a vertical bar or tube D, in which is cut a spirally disposed slot 19. A plate G, is securely attached to the top B, one end of said plate G, is shaped as a lug e, and fitted to work in the slot 19, also on the top B, is secured the center guide-ring 6. Near the lower end of said tube D, is placed an adjustable hub 9, that is provided with spider-legs 4, 4, 4, and on the lower end of said spider-legs are firmly attached cones 1, 1, 1. To the lower end of tube D, is fitted a threaded cap-nut 2, that carries a washer 3 made of rubber, leather, or other material that offers some friction to the hub 9. To retain the hub 9 near the washer 3, the tube D is fitted with a threaded lock-nut 5.

Near the upper end of tube D, a trunnioned sleeve 7, is fitted around tube D, and pivoted within a yoke n, one side of which is provided with a joint i, and is held by a bolt a, to a connecting bar Q; the said bar Q is

pivoted to an upright brace b, which is firmly attached to the outside of tub A; to the other end of the yoke n, is attached a socket s, within which is fitted handle h. The trunnioned sleeve 7 is vertically adjusted and held on the tube D, by a union 8, a ball-bearing ring 10, and balls 12, thumb-screw t, A bar may be used as a shaft, instead of the tube D.

A lamp C is shown beneath the machine for heating.

The purposes of the several parts may be more readily understood by a description of the working of the machine. Clothing to be washed is placed in the tub, and water supplied sufficient to cover them. The cones are placed on top of the clothes, and the handle is adjusted by the thumb-screw at nearly right angles to the tube D. The handle is then raised, whereby the tube D, and pounders, are raised and the latter rotated by the lug e, operating within the spirally disposed slot 19.

If the cones are free from any entanglement with the clothes, they are given, by the friction of the washer 3, the same motion as that imparted to the tube D, and are moved around the tub. When there is any considerable entanglement of the cones with the clothes, the cones do not rotate. When the handle is lowered and the cones strike the clothes, the friction of the clothes is greater than the friction of the nut 5, on the hub 9, and the cones are forced down vertically, without the axial turn, and each successive stroke of the handle causes the cones to strike at different places on the clothes, thus covering and subjecting every part of the clothes in the tub to the air and water forced through them by the cones.

Any means of heating the water may be used, the one form shown being for a movable tub with legs. The top, tightly closed as it is, prevents the escape of steam and heat and aids materially in the washing. When it is desired to open the washer, the handle h, is raised so that the lug e, catches at the bottom of the spiral slot 19, and raises the top B; and the pivoted connecting bar Q allows the cones 1, 1, 1, and all the inner operating parts, to be turned back out of the tub.

Having thus described my invention I claim as new and desire to secure by Letters Patent

An upright cylindrical tub, provided with

a top carrying a guide-plate, and a lug fitted to operate within a spirally disposed slot in a laterally reciprocating and axially rotating bar, carrying near the upper end a trunnioned sleeve, fitted with a union, and a ball-bearing ring with balls with a set screw; said

5 bar provided with a cap-nut, and carrying a washer and a hub fitted near the lower end;

the hub provided with a multiple of projecting arms and cones, with means for heating 10 the water in said tub, as and for the purposes described.

RICHARD HAYES.
